UNITED STATES PATENT OFFICE.

FRIDOLF SCHAUMAN, OF COPENHAGEN, DENMARK.

ELASTIC RAIL-SUPPORT.

SPECIFICATION forming part of Letters Patent No. 328,616, dated October 20, 1885.

Application filed December 3, 1884. Serial No. 149,723. (No model.) Patented in England December 15, 1883, No. 5,755; in France December 15, 1883, No. 139,190, and in Belgium December 15, 1883, No. 63,557.

To all whom it may concern:

Be it known that I, FRIDOLF SCHAUMAN, a citizen of Sweden, and a resident of Copenhagen, Denmark, have invented certain new and 5 useful Improvements in Elastic Rail-Supports, of which the following is a specification.

The object of my invention is to provide an improved device for fastening railway-rails upon their sleepers which will afford an elastic support to the rail, thereby reducing noise and vibration, prolonging the durability of the rails, track, and rolling-stock, and rendering travel on railroads more agreeable than heretofore.

15 The invention relates to a spring of steel or other suitable metal, adapted to be fastened upon the sleeper and to support the rail and keep it from lateral displacement. This steel spring I have principally adapted for fastening 20 rails to stone sleepers, such as shown in my patent of the United States No. 279,280, dated June 12, 1883; but it may also be successfully applied to sleepers of iron, wood, or other material, whether placed transversely or longitudinally under the rail.

The invention will be hereinafter described and claimed with reference to the accompanying two sheets of drawings, in which—

Figures 1 and 2 are plan views of my elastic rail-support in position, showing the manner of attaching it to the rail, the latter being indicated in dotted lines. Fig. 3 is a vertical section of the rail, its elastic support, and the sleeper, the section being taken on 35 the line *xx* of Fig. 2. Fig. 4 is a plan view of a modification of the same, and showing the rail in dotted lines. Fig. 5 is a section on *yy* of Fig. 4, showing also the supported rail in section. Figs. 6 and 7 are plan and edge 40 views, respectively, of another modification applied to a rail. Figs. 8 and 9 are plan and edge views, respectively, of a third modification of the same.

A designates the elastic rail-support, *b* the 45 sleeper, and *f* the rail. The support *A* is made preferably, though not necessarily, in one piece, of a plate of spring-steel, and consists of the flaps or lugs *a*, by which it rests upon and is secured (by spikes or bolts 50 through holes *n*) to the sleeper, and the in-

clined flaps *d*, which are the springs proper that give elastic support to the rails. The spring-flaps *d* are provided with upward and inward bent or reverted edges *e*, by which they embrace the opposite edges of the rail 55 flange or foot to prevent lateral displacement of the rail. The sleeper shown in Fig. 3 is supposed to be of stone, for which reason, instead of by spikes, the plate *A* is fastened to the sleeper by bolts and nuts, the bolt-holes 60 going entirely through the sleeper, and the lower end of the bolts being either wedged in the hole or protruding below it, and having a head against the under side of the sleeper, both of which fastening devices are shown in 65 Fig. 3. The fastening lugs or flaps *a* are arranged either obliquely opposite to each other and directly opposite to the spring-flaps *d*, as shown in Figs. 1, 2, 3, 4, 5, (in Figs. 4 and 5 one flap being intermediately opposite to two,) 70 or the flaps *a* are arranged directly opposite to each other intermediate to the spring-flaps *d*, as shown in Figs. 6, 7, 8, 9. The reverted or inward overturned outer flaps or edges, *e*, are formed either directly upon the upper or outer 75 ends of the inclines *d*, as in Figs. 1, 2, 3, or upon a horizontal extension, *h*, thereof, as in the remaining figures, the said extensions *h* serving as resting-planes for the rail-foot, with the object of increasing the bearing surface. Otherwise the rail is supported at the 80 edges only upon the upper end of the incline of the spring-flaps *d*, as in Fig. 3. The horizontal flap *a* is separated from the adjacent inclined edge of the spring-flap *d* by an incision or slit, *c*, which, when the plate *A* (constructed as in Figs. 2 and 4) is adjusted in position, is at right angles to the rail, but oblique thereto when constructed as in Fig. 8, 85 and which slit does not appear when the plate *A* is cut out, as in Fig. 6. The rectangular distance between inner surfaces of [the] opposite clamping-edges *e* should of course be the same as or very slightly in excess of the width across the rail-foot, and the distance 90 between them, measured in the oblique line, must be not less than the rectangular distance, in order to allow of attaching the spring-plate *A* to the rail. When this plate is narrow, the proper distance obliquely may be ob- 100

tained by beveling or cutting off the corner of the clamping-edge *e*, as in Figs. 1 and 2. Otherwise (see Figs. 8 and 9) this is not needed.

To show the manner of attaching the plate 5 *A*, the rail *f* is indicated in outline in Figs. 1 and 2. The plate is first placed under the rail obliquely to it, as in Fig. 1, to allow of entering the rail-foot between the edges *e*. It is then turned in the position of Fig. 2 to 10 clamp the opposite edges of the rail-foot, as in Fig. 3, and is then secured to the sleeper, as before stated. To avoid placing the plate obliquely for attaching it to the rail the edge 15 *e*, at one side of the rail, may be turned up only without being reverted, (as shown at *g* in Figs. 4 and 5,) and a screw, *i*, threaded through it to bear against the rail-flange.

It is evident that the thickness and other 20 dimensions of the steel plate *A* and the parts thereof must be made in proportion to the greatest weight it is intended to support and to the size of rail used.

This rail-spring may, if desired, be composed of several separate spring-blades instead of being made in one piece. The plate 25 *A* being fastened to a stiff under layer, an intermediate layer of pasteboard, rubber, wood, or other comparatively soft material may be placed under the same, thereby obtaining the 30 advantage (among others) that the driving on the rails is almost noiseless. The specific constructions shown in Figs. 4 and 6, which are not embraced under the generic features of the device, I reserve for special patent applications.

Having thus described my invention, I claim 35 as new and desire to secure by Letters Patent—

1. A metallic plate, *A*, adapted to be secured upon a railway-sleeper, and provided with rail-supporting flaps *d*, having reverted 40 edges to receive the rail-flanges, for the purpose set forth.

2. A metallic plate, *A*, having flaps or flanges *a*, adapted to be secured upon a railway-sleeper, and inclined spring-flaps *d*, the 45 said spring-flaps being provided with horizontal extensions *h*, having reverted edges *e*, to support and embrace the foot of the rail, substantially as and for the purpose specified.

3. A metallic plate, *A*, having flaps or flanges *a*, adapted to be secured upon a railway-sleeper, and inclined spring-flaps *d*, provided with reverted edges obliquely opposite to each other to embrace opposite edges of the rail-foot, substantially as and for the purpose specified.

4. A metallic plate, *A*, having obliquely-opposite lugs or flanges *a*, adapted to be secured upon a railway-sleeper, and adjacent to the said flanges rail spring-supporting-flaps *d*, which 60 have reverted edges and are separated from the flaps by a side slit, *c*, said spring-flaps being arranged obliquely opposite to each other and directly opposite to the flanges *a*, substantially as specified.

In testimony that I claim the foregoing as my invention I have signed my name, in presence of two witnesses, this 27th day of May, 1884.

FRIDOLF SCHAUMAN.
